his attorney.

UNITED STATES PATENT OFFICE

CHARLES J. FOERSTER, OF NEWTON, MASSACHUSETTS

FINGER NAIL POLISHER

Application filed September 27, 1929. Serial No. 395,709.

This invention relates to devices for polishing, brushing, filing or sanding finger nails or the like, and has for its principal object the provision of an improved, automatically-driven apparatus of this character, which is economical to manufacture, easy to operate, compact in structure, and durable and efficient in use. Particular features of the invention will be evident from the following description, taken in connection with the accompanying drawings, and will be pointed out in the appended claims.

In the drawings which illustrate a recommended embodiment of the invention, Fig. 1 is a side view, partly in longitudinal section, of the device; and Fig. 2 is an enlarged transverse section taken on line 2—2 of Fig. 1.

The apparatus chosen for the purpose of illustration comprises a base 1 having a sheet metal casing 2 mounted thereon; an electric motor 3 of usual construction housed within the casing and having a rotatable shaft 4 carrying an eccentric member or cam 5; a plunger 6 reciprocable within a bearing 7 supported within the casing and projecting therefrom, one end of the plunger having a head 8 in operative relation to the cam 5 by means of a helical spring 9, and its other end having an axial recess tightly receiving the reduced end 20 of a removable polishing or buffing tool 10. The tool 10 is polygonal in cross-section, and the end 20 is preferably square so that said end may be inserted in the complementary recess at the end of the plunger, to present one selected side of the tool for the brushing or polishing or other operation.

The respective sides or faces of the tool are formed with dovetailed grooves to receive removable brushing, polishing or sanding members indicated generally by the number 11. Said members have bases corresponding to the dovetailed grooves in the tool, as clearly shown in Fig. 2, and may be slid endwise into said grooves wherein they are frictionally retained. The working face-pieces of said members, for example the brush 21, sanding member 22, buffer 23 and beveled filing element 24, may be imbedded

in or fastened to the respective members in any usual manner.

A convenient support for the finger during the polishing operation is preferably arranged beneath the polishing tool. The structure illustrated comprises an upright bracket 12 mounted on the base 1; a lever or arm 13 centrally pivoted in the bracket and having platforms 14, 15 at its opposite ends and an elevated finger rest 16 between the one end and its fulcrum; a guide 18 having a slot 17 in which the lever has limited oscillation, and a spring 19 arranged normally to urge the finger rest 16 upwardly toward the polishing tool.

The operation of the device is extremely simple yet effective. Rotation of the cam 5 causes the plunger 6, which is normally urged in one direction (to the left of Fig. 1) by the spring 9, to reciprocate in cylinder 7, thereby imparting reciprocatory movement to the tool 10 and causing the brush, buffer or sanding device which is at the moment on the under side of the tool to move back and forth across the nail of the finger supported in properly elevated position on the rest 16. This finger will usually adjust the elevation of the support 16 by depressing the lever against the action of the spring 19 to accommodate the thickness of the particular finger operated upon, but other fingers of the same hand may bear upon the platform 15 to regulate the pressure upon the nail being polished; and if greater pressure is desired, the other hand may be pressed upon the opposite platform 14. Hence the apparatus may be conveniently and satisfactorily operated by a single person, without the attendance of a trained operator; so that the device may be used in the home as well as in a professional manicuring establishment.

It will be noted that the action of the cam 5 imparts a reciprocating movement which varies the speed of the plunger 6 during its opposite traverses, the degree of acceleration depending upon the shape of the cam. The brush or buffer hence moves at a constantly changing speed which is most beneficial in attaining the desired results.

It is, of course, apparent that the rotation

of the cam may be produced by a variety of mechanical devices, either automatic such as a clockwork mechanism, or hand-driven, as well as by a common type of electric motor shown at 3 in Fig. 1, and that other details 5 of the structure herein described may be varied to suit particular purposes without departing from the essence of this invention as defined in the following claims.

I claim:

10 1. Apparatus of the class described comprising a plunger, a tool removably connected to the plunger at one end, the tool having a plurality of faces and having cleaning or 15 polishing elements mounted on the respective faces, the tool being angularly adjustable with respect to the plunger so that any selected element may be positioned upon the under side of the tool, a finger support spaced beneath the tool, and means for reciprocating 20 the plunger.

25 2. Apparatus of the class described comprising a plunger having a recess in one end, a tool having a reduced end fitting in said recess removably to interconnect the tool and 30 the plunger, said end and said recess being polygonal in cross section so that the parts may be angularly adjusted with respect to each other, the tool having several longitudinal faces, a cleaning or polishing element mounted on each face of the tool for selective arrangement on the under side of the tool, a finger support spaced beneath the tool, and means for reciprocating the plunger.

35 3. Apparatus of the class described comprising a plunger having a recess in one end, a tool having a reduced end fitting in said recess removably to interconnect the tool and 40 the plunger, said end and said recess being polygonal in cross section so that the parts may be angularly adjusted with respect to each other, the tool having several longitudinal faces, a cleaning or polishing element 45 removably mounted on each face of the tool for selective arrangement on the under side of the tool, a finger support spaced beneath the tool, and means engaging the opposite 50 end of the plunger for reciprocating the plunger and tool.

55 4. Apparatus of the class described comprising a plunger, a cleaning and polishing tool removably connected to the plunger at one end, the tool being angularly adjustable with respect to the plunger, resilient means normally urging the plunger in one direction, a cam bearing upon the opposite end of the plunger, and means for rotating the cam to move the plunger in the opposite direction 60 against the action of said resilient means.

65 5. Apparatus of the class described comprising a reciprocating plunger, having a head at one end and a recess in its opposite end, a cleaning and polishing tool having one end removably mounted in said recess, a cam bearing against said head, a spring nor-

mally urging the head toward the cam, and means for rotating the cam to reciprocate the plunger.

6. Apparatus of the class described comprising a cylinder, a reciprocating plunger, 70 in the cylinder, a cleaning and polishing tool at one end of the plunger, a head at the opposite end of the plunger, a cam bearing against said head, a coiled spring surrounding the plunger and bearing against said 75 head and against the end of the cylinder, and means for automatically rotating the cam to reciprocate the plunger.

7. Apparatus of the class described comprising a plunger, a tool removably connected to the plunger at one end thereof, the tool having a plurality of faces, cleaning or 80 polishing elements detachably mounted upon the respective faces of the tool, the tool being angularly adjustable with respect to the 85 plunger so that any selected element may be positioned upon the under side of the tool in operative relation to a finger held therebeneath, and means for reciprocating the plunger to move the cleaning or polishing 90 element across the finger nail.

8. Apparatus of the class described comprising a plunger, a tool removably connected to the plunger at one end thereof, the tool having a plurality of faces, cleaning or 95 polishing elements detachably mounted upon the respective faces of the tool, each face having a longitudinal groove and each of said elements having a base portion slidably endwise into said groove, the tool being angularly adjustable with respect to the plunger so that any selected element may be positioned upon the under side of the tool in operative relation to a finger held therebeneath, and means for reciprocating the plunger to 100 move the cleaning or polishing element across the finger nail.

In testimony whereof I affix my signature.
CHARLES J. FOERSTER.
